UNITED STATES PATENT OFFICE.

SAMUEL FORTER, OF PITTSBURGH, PENNSYLVANIA, ASSIGNOR TO H. L. DIXON COMPANY, OF PITTSBURGH, PENNSYLVANIA, A CORPORATION OF PENNSYLVANIA.

REVERSING VALVE.

Application filed January 19, 1923. Serial No. 613,791.

To all whom it may concern:

Be it known that I, SAMUEL FORTER, a citizen of the United States, residing at Pittsburgh, county of Allegheny, and State 5 of Pennsylvania, have invented a new and useful Improvement in Reversing Valves, of which the following is a full, clear, and exact description:

The present invention relates to valves, 10 and more particularly to air reversing valves.

It has heretofore been proposed to provide a reversing valve for gas-fired furnaces, comprising a base member having a 15 central port therein for communication with the chimney and two end ports for communication with the furnace and a hood movable to alternately cover the central and one of the end ports, and then to cover the 20 central and the other end port. In this construction of valve, however, there was no regulation provided for the flow of fluid through the port left uncovered by the hood, except through the mushroom valve at the top of 25 the valve casing. In an air reversing valve for regenerative furnaces, it has been found desirable to provide for the independent regulation of the flow of air through the two outside ports leading to the regenerators. 30 The present invention provides a valve embodying this desired feature.

The invention is illustrated in the accompanying drawings, in which:

Figure 1 is a plan view of a valve constructed in accordance with one embodiment of my invention.

Figure 2 is a side elevation of the valve shown in Figure 1.

Figure 3 is a vertical longitudinal sectional view of part of the valve structure shown in Figure 1.

Figure 4 is a vertical longitudinal sectional view of a modified form of valve, a portion of the furnace being shown in section also.

Referring to the construction shown in Figures 1, 2 and 3, the reversing valve therin shown comprises a base 2 in the form of a rectangular pan adapted to be 45 supported upon the masonry of the furnace with its central port 3 in communication with the chimney, and with its two end

ports 4 and 5 in communication with the regenerators.

Mounted for movement longitudinally of 55 the base 2 is a hood 6 adapted to alternately cover the central port 3 and end port 4 and the central port 3 and end port 5. Secured to the opposite ends of the hood 6 are a pair of axles 7, each axle having a pair of flanged 60 wheels 8 journaled upon its opposite ends. The opposite sides 9 of the base 2 constitute tracks for the wheels 8.

The base pan 2 normally holds a quantity of water into which the lower edges of 65 the hood extend to form a seal therefor. The sides 9 of the base have cam surfaces 10, 11, 12 and 13 provided in their upper edges for cooperation with the wheels 8 for lifting the hood at the beginning of its 70 travel in either direction sufficiently to permit the lower end edges 14 of the hood to clear the tops of the ports 3, 4 and 5. Thereafter, the hood travels with a straight line movement until it reaches the end of 75 its travel, when the cam surfaces 10 and 12 or 11 and 13 permit the hood to lower to bring its end edges 14 beneath the surface of the sealing fluid. Suitable means, such as cables 15, may be provided for moving 80 the hood in opposite directions.

Fastened to each of the opposite ends of the hood 6 are a pair of brackets 16. Pivotally connected at its lower end to each bracket is a lever 17. Each bracket is provided with a pair of stop members 18 and 19 for limiting the swinging movement of the corresponding lever 17. The upper ends of the pair of levers 17 at each end of the hood are connected by a transverse shaft 20, 85 and suspended from each shaft 20 by means of bolts 21. The upper end of the shaft 20 is a valve member 22. The shafts 20 pass freely through eyes formed integral with the upper ends of the bolts 21, while the lower end portions of the bolts are 90 screw-threaded throughout a considerable portion of the length of each bolt. The threaded end portions of the bolts 21 pass through suitable openings in the valve members 22, and the latter are secured in position on the bolts by means of nuts 23 and 24. If desired, a stiffening member 25 may be interposed between the valve member 22 and the nuts 23.

Fastened to each of the opposite ends of the base 2 are a pair of standards 26. The upper end portions of each pair of standards are bent inwardly towards the corresponding end of the hood, and joining the upper ends of each pair of standards is a transverse shaft 27. Journaled upon each of the shafts 27 is a pair of anti-friction rollers 28. The rollers 28 cooperate with the levers 17 to raise the valve members 22 from the position shown at the right hand end of Figure 2 to the position shown at the left hand end of said figure.

The operation of the valve shown in Figures 1, 2 and 3 is as follows: With the parts in the position shown in Figure 2, the hood 6 covers the ports 3 and 4 and a valve member 22 is in a position to control the port 5. The exhaust gases from the furnace 15 enter the hood 6 through the port 4 after passage through a regenerator and escape through the port 3 to the chimney. At the same time air enters the partially closed port 5 and passes to the corresponding regenerator. The amount of air entering the port 5 may be regulated by adjusting the valve member 22 on the threaded bolts 21. When it is desired to reverse the direction of flow of the incoming air and of the exhaust gases, 20 the hood 6 is moved to the right, Figure 2. At the beginning of this movement, the cam surfaces 10 and 12 cooperate with the wheels 8 to raise the hood sufficiently for its lower end edges to clear the top edges of the ports 3 and 4. Thereafter, the hood travels on an even level until the cam surfaces 11 and 13 are reached, when the hood again lowers to cover the ports 3 and 5. During the movement of the hood to the right, the levers 17 25 at the right hand end of the hood engage the corresponding anti-friction rollers 28, whereby the right hand valve member 22 is raised into a position corresponding to that of the left hand valve member 22, Figures 2 and 3. At the same time, the levers 17 at the left hand end of the hood cooperate with the corresponding rollers 28 to permit the left hand valve member 22 to lower by gravity into a position to control the port 4. It 30 will be seen that either valve member 22 may be adjusted independently of the other for regulating the amount of air flowing through the port which it controls.

In the modified construction shown in Figure 4, a slightly different arrangement is provided for raising and lowering the valve members 22. Each valve member 22 is suspended by means of a single bolt 21' fastened at its upper end to a transverse shaft 20', the latter being journaled at its opposite ends in the inner ends of toggle levers 17' and 29, the levers 17' being journaled at their outer ends upon the opposite ends of the axle 7 which carries the flanged wheels 8 and the outer ends of the levers 29 being journaled

to the side walls of the base 2 adjacent the ends thereof. The operation of this form of the invention will be obvious from an inspection of Figure 4.

The advantages of the present invention 70 arise from the provisions in combination with a hood of separate and independently adjustable valves for regulating the quantity of air supplied to the furnace.

I claim:

1. In a valve, a base having a plurality of ports therein, a hood movable to alternately cover and uncover one of said ports, a valve connected to and movable relatively to the hood for controlling said port when uncovered by said hood, and means carried in part by said hood and in part by said base for supporting and actuating said valve substantially as described. 80

2. In a valve, a base having a plurality of ports therein, a hood movable to alternately cover and uncover one of said ports, a valve movable relatively to the hood for controlling said port when uncovered by said hood, and means carried in part by said hood and in part by said base for supporting and actuating said valve, said valve being adjustably connected to its supporting means for varying the flow through said port, substantially as described. 90

3. In a valve, a base having a plurality of ports therein, a hood movable to alternately cover and uncover one of said ports, a valve for controlling said port when uncovered by said hood, supporting means for said valve pivotally connected to said hood, and abutments secured to said base and arranged to engage said supporting means and thereby move said valve to inoperative position upon movement of said hood into a position 100 covering said port, said supporting means moving by gravity to carry said valve to operative position upon movement of said hood into a position covering said port, and stops carried by said hood for limiting the 105 movements of said supporting means, substantially as described. 110

4. In a reversing valve, a hood for controlling a plurality of ports, said hood being movable to successively cover or uncover certain of said ports, controlling means bodily movable relatively to said hood for co-operation with a port when uncovered by said hood, and means carried at least partly by said hood for maintaining said controlling means at all times in spaced relationship to the port to be controlled thereby and for bodily moving said controlling means relatively to the hood into operative relation to the port as the hood is moved out of operative relation thereto, substantially as 115 described. 120

5. In a reversing valve, a hood for controlling a plurality of ports, said hood being movable to successively cover or uncover 130

certain of said ports, controlling means bodily movable relatively to said hood for co-operation with a port when uncovered by said hood, and means carried at least partly by said hood for maintaining said controlling means at all times in spaced relationship to the port to be controlled thereby and for bodily moving said controlling means

relatively to the hood into operative relation to the port as the hood is moved out of operative relation thereto, said controlling means being at all times exterior to the hood, substantially as described.

In testimony whereof I have hereunto set my hand.

SAMUEL FORTER.
